UNITED STATES PATENT OFFICE.

CARL F. BUCK, OF SALT LAKE CITY, UTAH.

PRINTING-PRESS.

No. 861,706.

Specification of Letters Patent.

Patented July 30, 1907.

Application filed November 23, 1905. Serial No. 288,752.

To all whom it may concern:

Be it known that I, CARL F. BUCK, a resident of Salt Lake City, in the county of Salt Lake and State of Utah, have invented certain new and useful Improvements in 5 Printing-Presses; and I do hereby declare the following to be a full, clear, and exact description of the invention, such as will enable others skilled in the art to which it appertains to make and use the same.

My invention relates to improvements in printing 10 presses, and more particularly to cylinder presses, an object of the invention being to provide an automatic cylinder printing press for flat type with improved cylinder movable across the same, comprising light movable parts capable of a very high speed, and at the same 15 time requiring very little power to run the press and which is built on much more simple lines than other cylinder presses in use at the present time.

A further object is to provide improved mechanism 20 for automatically moving the type out of the path of the cylinder when the latter fails to take a sheet to be printed upon.

A further object is to provide improved inking mechanism operated by the cylinder mounting.

A further object is to provide improved paper feeding 25 and ejecting means and improved means for transmitting motion to all movable parts to compel them to act in unison and at the proper time.

With these and other objects in view, the invention 30 consists in certain novel features of construction and combinations and arrangements of parts as will be more fully hereinafter described and pointed out in the claims.

In the accompanying drawings, Figure 1 is a top plan view. Fig. 2 is a view in side elevation. Fig. 3 is a 35 view in front elevation. Fig. 4 is a view in section on the line A—A of Figs. 1 and 2. Fig. 5 is a view in section on the line B—B of Figs. 1 and 3 showing the impression cylinder after it has taken a sheet of paper and is passing over the face of the type. Fig. 6 is a view 40 similar to Fig. 4 showing impression cylinder in position to take sheet of paper from feed table. Fig. 7 is a view similar to Figs. 4 and 5 showing impression cylinder after it has taken a sheet of paper and is passing under and lifting up hinged portion of feed table. Fig. 8 is a 45 view in section on the line C—C of Figs. 1 and 3 showing impression cylinder in position to deliver a sheet of paper after it has been printed, and also shows the inking rollers just starting to pass over the face of the type. Figs. 9 and 10 show the gear wheels and inking rolls 50 thereon, and Figs. 11, 12 and 13 are enlarged detail views of impression cylinder and paper feeding mechanism.

1 represents a bed plate having standards 2 constituting the frame-work support of my improved mechanism. These standards 2 are made with openings to

receive the cylindrical ends of a hollow connecting axle 3 securely fastened to the standards and secured against turning by clamps 4. Large gear wheels 5 are mounted to turn about the cylindrical end positions of axle 3 and are driven by pinions 6 in mesh therewith and secured upon a driven shaft 7 having a pulley 8 thereon to receive motion from any desired motor, and the turning of the gear wheels 5 serves to drive all working parts of my improved printing press as will be more fully hereinafter set forth. The axle 3 at its intermediate portion between the gear wheels 5, is made in the form of a supporting table, as shown most clearly in Figs. 4 and 8, and will be hereinafter referred to as the table portion of axle 3. This table is provided at four points with openings in which four vertically movable pins 9 are mounted and are screw threaded at their upper ends to screw into internally threaded depending cylindrical lugs 10 on the under face of a plate 11 supporting the type chase 12. The pins 9 are made with angular enlargements 13 to receive a wrench and facilitate their adjustment in the lugs 10 and said lugs are made with movable thread bearing blocks 14 which are adjusted by set screws 15 to clamp the pins 9 and prevent any possibility of accidental turning movement thereof after being properly adjusted.

In horizontal recesses 16 in the table portion of axle 3 extending below the rounded or beveled lower ends of pins 9, horizontal supporting pins 17 are located and are beveled or contracted at their outer ends to form cams to raise or lower the pins 9 and plate 11 and coiled springs 18 are located on pins 17 and bear against annular shoulders 19 thereon to exert pressure on the pins 17 to force them inward when permitted.

A shaft 20 extends longitudinally through the hollow axle 3, is mounted to turn therein, and opposite to the inner ends of the pairs of horizontal pins 17, is provided with double cams or eccentrics 21, which latter are rigidly secured to the shaft 20 and when in one position hold the pins 17 projected outward to support the type chase in its normal operative position, but when the shaft is permitted to be turned by a coiled spring 22 thereon, the cams or eccentrics 21 will permit the springs 18 to draw the pins 17 inward and compel the plate 11 and type to fall by gravity to a position below its normal operative position.

A crank arm 23 is secured on one end of shaft 20 and is normally held by a pivoted dog 24, which latter is released by mechanism to be hereinafter described, when my improved impression cylinder 30 fails to take a sheet of paper to be printed upon.

The gear wheels 5 above referred to, are connected by cross rods 26 which compel them to move together as a movable carriage or carrier and said gear wheels are made with aligned radial slots 27, in which bearing boxes 28 are mounted to slide and coiled springs 110

- 29^a connect the boxes 28 with the inner ends of slots 27 and exert a continuous inward pull on the boxes 28. These bearing boxes 28 provide rotary mounting for alined tubular shafts 29 on which the hollow impression cylinder 30 is mounted and located between and rigidly secured to diks or heads 31 on shafts 29 compelling the cylinder 30 and shafts 29 to turn together and the shafts to act as trunnion supports for the cylinder ends.
- 10 Pinions 32 are secured on shafts 29 close to the ends of cylinder 30 and mesh with racks 33 secured to stationary axle 3, and said racks are of circular form throughout their greater portions but have horizontal or flat portions which are located parallel with the face 15 of the type 34.

On the outer ends of shafts 29, rollers 35 are secured and run on tracks 36 of the same shape, and disposed like racks 33. The tracks 36 are secured to standards 2, and the tracks 36 and rollers 35 are just the 20 proper size to allow the pitch lines of pinions 32 to reach the pitch lines of racks 33.

Horizontal guide bars 37 are secured to the upper ends of standards 2 and are located above and parallel with the flat or horizontal portions of tracks 36, and 25 said bars 37 are spaced from tracks 36 a distance approximating the diameter of rollers 35 to hold the latter on tracks 36 and the pinions 32 on racks 33 during the horizontal movement of the impression cylinder, to insure a proper contact of the paper sheet with the 30 type.

A rod 38 is mounted in tubular shafts 29 and extends through the impression cylinder 30 and projects out beyond the end of one tubular shaft 29 as shown. A sleeve 39 is secured on rod 38 in cylinder 30 and a coiled 35 spring 40 is located on the rod and bears at one end against a shaft 29 and at its other end against the sleeve 39 to normally hold the end of rod 38 projected outward, and this outward movement of the rod is limited by a collar 41 secured thereon. A triangular plate or arm 40 42 is secured to sleeve 39, projects up through a slot in cylinder 30 and is provided at its apex or end with a rounded lug or roller 43 located in a spiral or cam groove or slot 44 in a sleeve 45 secured upon a shaft 46, the latter mounted to turn in bearings 47 in a longitudinal 45 recess in cylinder 30 and provided with a series of gripper fingers 49. A coiled spring 49^a is located on this shaft 46, is secured at one end to the shaft and normally holding the gripper fingers 49 in position to clamp a paper sheet to the impression cylinder. By this 50 construction and arrangement of parts it will be seen that when the projecting end of rod 38 engages an elongated cam enlargement 50 on a standard 2, the rod will be forced inward, and the plate or arm 42 will move and compel sleeve 45 and shaft 46 to turn, by reason 55 of the engagement of the end of the arm 42 in spiral groove or slot 44, and thereby move the gripper fingers 49 back into a recess 51 provided in the cylinder, as shown in Fig. 6, so that when the sheet is fed to the cylinder from the platform the gripper fingers will be 60 out of the way, but at the proper time the rod 38 will have passed the cam enlargement 50 and the springs 40 and 49 will return the parts to their former normal positions, to compel the fingers to grasp the end of the sheet to be printed upon and after the sheet is printed 65 upon and the cylinder reaches the predetermined po-

sition, the projecting end of rod 38 will engage the end of enlargement 50 to release the printed sheet and drop the same, printed side up, into a receptacle 54 provided for the purpose.

The gear wheels 5 are provided with three parallel 70 slots 53 having bearings 54^a which are mounted to slide in the slots and coiled springs 55 are located in the outer ends of the slots and exert inward pressure on the bearings and on inking rolls 58 having their trunnions 59 located in the bearings and provided with 75 small wheels 60 mounted to run on tracks 61 secured to, and conforming in shape to the racks 33, the springs 55 serving to hold the wheels 60 on their tracks 61 and compelling the inking rolls to move across the type 34 to ink the same.

Two slots 62 are provided in gear wheels 5 parallel with slots 53 and arranged between the slots 53. Bearings 63 are mounted to slide in the slots 62 and coiled springs 64 connect the inner ends of the slots 62 with the bearings 63 to exert an inward pull on the bearings 85 63 and on vibrating rolls 65, the elongated trunnions of which are mounted in the bearings so as to hold the vibrating rolls against the inking rolls 58.

In advance of, and in rear of the slots 53 and 62, slots 66 are located in gear wheels 5 and bearings 67 are 90 mounted to slide in the slots 66 and are pressed inward by coiled springs 68 in the outer ends of the slots to hold in proper position inking rolls 69, the trunnions of which latter extend through the bearings and are provided with wheels 70 to run on tracks 61 but are located in a different plane from the wheels 60 so that wheels 60 and 70 will run over different parts of tracks 61. Slots 71 are provided between slots 66 to slidably mount bearings 72 supporting the trunnions of 95 vibrating rolls 73 contacting with rolls 69 and springs 74 are located in the outer ends of slots 71 to hold the vibrating rolls in contact with inking rolls 69.

75 represents a curved ink plate having webs 76 made dovetailed to fit in dovetailed grooves in the bottom of the table portion of axle 3 and are secured in 105 place therein by set screws.

The ink receptacle 77 comprises a three sided frame pivotally secured to axle 3 as shown, and the outer side of the ink receptacle formed by a roller 78 the trunnions of which being supported in the end walls of receptacle 110 77 and one of which trunnions which projects through the receptacle, is provided on its outer end with a star wheel 79 which at every revolution of the gears 5 is engaged by a lug 80 on one of said gears to partially rotate the roller 78 and present a new ink face to the ink rolls 115 69 which touch the same and the ink thus received is smeared by the vibrating rolls 73 and is deposited on ink plate 75 and from the latter the rolls 58 receive the ink and pass across the type to ink the same. A spring plate 81 constitutes the bottom of receptacle 77 120 and is held up against roller 78 by thumb screws 82 and the receptacle is held in operative position by pins 17 and when the latter move inward to drop the type, the ink receptacle will also move out of the path of the ink rolls 69.

Cam enlargements 83 are provided on tracks 61 at the ink receptacle 77 so that the wheels 60 of ink rolls 58 will hold the latter away from roller 78 but these enlargements are out of the path of wheels 70 and do not interfere with the contact of rolls 69 with roller 78 and 130

as the slots 66 are too short to permit the rolls 69 to engage the type, they will be held away from the type and only rolls 58 will come into contact with the type.

The crank arm 23 above referred to is provided near 5 its end with a sleeve 84 in which a pin 85 is held at right angles to the arm, and a similar pin 86 is supported in a sleeve 87^a on the dog 24. This dog 24 is pivotally secured to the frame and held in normal engagement with the arm 23 by a spring 24^a and is released by a 10 cam 151 on a gear wheel 5, as will more fully hereinafter appear. A shaft 87 is supported in bearings 88 on a standard 2, is located in an inclined position, as shown, and held against longitudinal movement by a clamping collar 89 and fingers 90 and 91 are secured to 15 said shaft 87 and project in opposite direction, one being shown over the pin 85, with the crank arm 23 in its ordinary operatiye position. On the upper end of shaft 87 a forked bracket 92 is secured and for convenience of reference I will designate the two arms or 20 fingers of the bracket 93 and 94, and a spring 96 holds the shaft 87 in position.

Securely fastened to standards 2, are brackets 99 and 100, to which a frame 101 is secured and supports a horizontal metal plate 102 forming a portion of a paper 25 feed table. A short shaft 103 is secured at one end to a frame 104 and is journaled in bearings 105 and 106. This shaft is made angular throughout its length, save at its bearing supports, and a sleeve 107 having an angular bore is mounted on this shaft 103 and is provided with arms 108 and 109 to engage the fingers 93 and 94 as will be hereinafter explained.

Above shaft 103 and parallel therewith, a shaft 112 is supported in bearings 113 and held against accidental turning by a coiled spring 95. The shaft 112 is also 30 made angular throughout except at its bearings, and has an arm 114 secured thereon and normally resting on a lug 96 on bracket 99 to limit the turning movement of the shaft 112 and a cam 111 is secured on shaft 112 and located between pins 110 on sleeve 107. An angularly 35 bored sleeve 115 is located on shaft 112 is secured by a set screw 116, and provided with a rearwardly projecting arm 117 and an opening 118 is provided in the sleeve 115 to accommodate a crank arm 126 having an angular hole to receive shaft 112. This sleeve 115 also forms a 40 journal on which a forked bracket 119 is fulcrumed, the forward open end of said bracket supporting a wheel 122 and the rear closed end of the bracket lying below arm 117. The wheel 122 is provided at the upper portion 45 of its periphery with a bifurcated lug 123 in which one end of a rod 125 is secured, the rear end of said arm being connected with the upper end of crank arm 126.

While short shaft 103 serves as a hinge for one side of frame 104, a short shaft 127 at the opposite side thereof serves a like purpose, and a plate 124 secured on frame 50 55 104 constitutes the front portion of the paper feeding platform and lugs 129 on brackets 99 and 100 limit downward movement of this hinged portion of the platform.

A shaft 130 is mounted in bearings 128 on frame 104 60 and is provided at suitable intervals with jogging fingers 131 and also has an arm 132 secured to one end and a collar 133 on its other end to hold the shaft against longitudinal movement.

One of the gear wheels 5 is provided with a radial slot 65 145, in which a sliding block 146 is mounted and a

spring 147 is located between the inner end of the slot and the block to press the latter outward. The block is provided at its ends with lugs 148 and 149 respectively and a tapered lug or enlargement 150 is located beside lug 148. A cam 151 is secured to this same gear wheel 5 70 and is provided with a tapered lug or projection 152, the operation of these lugs being hereinafter pointed out in the description of the operation of the paper feeding mechanism.

On one rod 26 connecting gear wheels 5 and located 75 at one side of the impression cylinder 30, fingers 153 and arms 154 are mounted and are all connected to move together, by a rod 155 passing through them. The ends of arms 154 are held against the hubs of pinions 32 by means of a spring 156 located on the rod 26. On the 80 rod 26 at the other side of impression cylinder 30, fingers 157 and arms 158 are located and connected by a rod 159 passing through them and the ends of arms 158 are held against the hubs of pinions 32 by a spring 160.

The type chase above referred to as being supported 85 on plate 11, is held in place by springs 134 and clamp 135. The clamp 135 is held by a screw 136 which passes through it and is provided with round projections 137 at its ends, journaled in bearings 138 on plate 11. On one of the round projections 137 is a set collar 139 and 90 the other round projection is made angular to receive a wrench and at the ends of clamp 135 are guide bars 140 which slide in angular slots 141 in bottom of plate 11.

The operation of my improvements is as follows:— When the press is started, a sheet of paper is deposited 95 on the feed table or platform and is pushed up against jogging fingers 131. The impression cylinder 30 which is now being carried around by gear wheels 5 is being also revolved by its gears 32 running on rack 33, and is carried up under hinged part of the feed table to a position as shown in Fig. 6. The rod 38 which passes through said cylinder has been pushed in by the cam enlargement 50 on standard 2, which by the mechanism above described, throws the gripper fingers 49 back to the position shown in this view (Fig. 6). When the cylinder 100 moves slightly further the rod 38 will move off enlargement 50 and permit the gripper fingers to move through recesses in the feed table and grasp the end of the paper sheet thereon. Previous to this operation, the jogging fingers 131, are elevated by means of arm 132 which is 105 engaged, and elevated by the hub of a pinion 32 coming up against the same. As the impression cylinder 30 moves upward it lifts the forward hinged part of the feed table up against wheel 122, as shown in Fig. 7 which movement of the hinged table also serves to turn 110 shaft 103. The sheet of paper is now being pulled off the feed table and by its contact with wheel 122 causes the latter to turn, and as the wheel is connected by rod 125 with crank 126 the shaft 112 will be turned and cause its cam 111 to move sleeve 107 out to the end of 115 shaft 103 to bring its arm 109 out under finger 94 of bracket 92 secured on shaft 87. As the sleeve 107 is turned by means of shaft 103 it presses arm 109 up against finger 94 and rocks shaft 87. This rocking of shaft 87 causes finger 91 to push pin 85 inward, as it is 120 assumed that the crank arm 23 is in the position shown by dotted lines in Fig. 2. This pin 85 is engaged by the projection 148 on sliding block 146 in gear wheel 5 which carries crank arm 23 to the position shown in full lines and as this movement of crank arm 23 turns shaft 130

20 and compels the eccentric 21 to force pins 17 outward and elevate pins 9, the type chase will be moved up to its normal printing position. When the crank arm has moved to this position, the block 146 strikes a 5 projection not shown on the frame work which causes the block 146 to move in its slot and release pin 85 and the latter is moved outward to its normal position by the tapered projection 150. The arm 23 when moved to this position is caught by dog 24 and held.

- 10 It will now be seen that if a sheet of paper is not caught and pulled off the feed table by the gripper fingers 49, the wheel 122 is not revolved, therefore the shaft 112 with cam 111 thereon, is not revolved and the sleeve 107 is not moved out to the end of shaft 103.

15 Hence when shaft 103 turns the arm 108 will engage finger 93 and rock shaft 87 in a direction opposite to that above described, causing the finger 90 to push pin 86 into the path of cam 151 which strikes the latter and forces the dog downward, releasing crank arm 23 and

20 permitting the latter to move to the position shown by dotted lines in Fig. 2. This causes the type chase to drop as above explained and the impression cylinder will pass over the same without contact with the type. The movement of crank arm 23 is limited by an enlargement on the frame. It will thus be observed that when the impression cylinder is taking the paper regularly the type are held up, but if the cylinder fails to take a sheet of paper, the type will be automatically dropped down out of the path of the cylinder and remain in such position until the cylinder again properly takes a sheet of paper to be printed upon.

25

30

When the impression cylinder takes a sheet of paper from the feed table, it moves forward and is caused to turn by the mechanism explained. This rolls the sheet 35 around the cylinder, which latter now rolls over the face of the type as shown in Fig. 5. After the sheet has been printed, the cylinder moves to the position shown in Fig. 8. Here the gripper fingers are thrown back by means of the rod 38 engaging cam enlargement 50 and 40 the sheet is released from the cylinder and is rolled off and dropped into the basket under the press, printed side up.

The ink rolls 69 in passing the supply roller 78 touch the same and receive their supply of ink, which is distributed over them by vibrating rolls 73 and supplied to plate 75. The rolls 58 are held out of contact with supply roller 78 by means of the enlargements 83 on tracks 61 but they contact with the plate 75 and only these latter rolls 58 contact with the type as the rolls 69 are held away from the type as shown in Fig. 8, and as above explained, when the type is dropped because the impression cylinder fails to take a sheet of paper the ink reservoir moves back to stop the supply of ink.

It will be noticed that the tracks 61 are a smaller radius than the pitch line of racks 33 which allows the impression cylinder 30 to pass the ink supply roller 78 and plate 75 without contact with either

A great many slight changes might be made in the general form and arrangement of the parts described without departing from my invention, and hence I do not restrict myself to the precise details set forth but consider myself at liberty to make such slight changes and alterations as fairly fall within the spirit and scope of my invention.

Having fully described my invention what I claim as 65
new and desire to secure by Letters-Patent, is:-

1. In a printing-press, the combination with a movable type support, of a rotary cylinder movable across said support and means controlled by the feed of a paper sheet to retain said support stationary, said means permitting the type support to move away from the path of the rotary cylinder when the paper fails to feed. 70

2. In a printing press, the combination with a vertically movable type support, of a rotary cylinder constructed to roll across the type and press a sheet thereon against the type, and means controlled by the feed of a sheet drawn onto the cylinder, for retaining the type support stationary and permitting said type support to drop away from the path of movement of the rotary cylinder when the latter fails to feed a sheet. 80

3. In a printing press, the combination with an approximately stationary type support, of an impression cylinder; means for revolving the cylinder and moving it over the type, and mechanism operated by the feed of paper sheets to control the position of the type chase. 85

4. In a printing press, the combination with a frame, of a type support secured in the frame, gear wheels at opposite sides of the type support and locked to turn together, a rotary impression cylinder supported in said gear wheels, means for revolving the cylinder as it is carried around the type support, spring pressed gripper fingers on the cylinder to grasp the end of a sheet to be printed upon; a rod carried by the cylinder, and constructed to release the gripper fingers when the rod is moved longitudinally, and an enlargement on the frame in the path of said rod to control the operation thereof. 90

5. In a printing press, the combination with a frame, a type support secured in the frame, and gear wheels at opposite sides of the type support and locked to turn together, of a rotary impression cylinder supported in said gear wheels, means for revolving the cylinder as it is carried around the type support, gripper fingers, a shaft located in a recess in the cylinder and to which the gripper fingers are secured, a sleeve on said shaft having a cam or spiral groove therein, a longitudinally movable rod in the cylinder, an arm on said rod located in the cam or spiral groove, and means on the frame engaged by the rod to throw the gripper fingers back into the said recess in the cylinder. 100

6. In a printing press, the combination with a frame, a type support secured in the frame, and gear wheels at opposite sides of the type support and locked to turn together, of an impression cylinder carried by the gear wheels, grippers on the cylinder for engaging and holding a sheet of paper, means for holding the type up to a position to print upon the paper on the cylinder, and mechanism operated by the sheet of paper to compel the said means to hold the type up to its work. 110

7. In a printing press, the combination with a frame, a type supporting table secured in the frame, and gear wheels at opposite sides of the table locked to turn together, of an impression cylinder carried by the gear wheels, a type supporting plate, a type chase thereon, vertical movable pins secured to the plate and located in opening in the table, horizontally movable beveled pins below the vertical pins and supporting the latter, eccentrics engaging the horizontal pins to force them outward and hold the type in its highest position, springs exerting inward pressure on the horizontal pins, and means operated by the cylinder when the latter fails to take a sheet of paper, to compel the eccentric to move, permit the horizontal pins to move inward and the type supporting plate to fall below its operative position out of the way of the impression cylinder. 120

8. In a printing press, the combination with a frame, a type supporting table secured in the frame, and gear wheels at opposite sides of the table locked to turn together, of an impression cylinder carried by the gear wheels, a type supporting plate, a type chase thereon, vertical movable pins secured to the plate and located in opening in the table, horizontally movable beveled pins below the vertical pins and supporting the latter, eccentrics engaging the horizontal pins to force them outward and hold the type in its highest position, springs exerting inward pressure on the horizontal pins, and means operated by the cylinder when the latter fails to take a sheet of paper, to compel the eccentric to move, permit the horizontal pins to move inward and the type supporting plate to fall below its operative position out of the way of the impression cylinder. 130

8. In a printing press, the combination with a type supporting table and an impression cylinder constructed to move around the same, of a type supporting plate, vertical pins secured to the plate and located in openings in the table, inwardly spring pressed horizontal pins supporting the vertical pins and having beveled ends to permit the plate to fall when the horizontal pins move inward, a shaft in the table, eccentrics thereon engaging the horizontal pins to project them outward, a crank arm on one

- end of the shaft, a spring on the shaft tending to turn the same to release the horizontal pins, and mechanism controlled by the feed of paper sheets to the cylinder to control the position of the crank arm.
5. In a printing press, the combination with a vertically movable type supporting plate and an impression cylinder constructed to move over the same, of a shaft, means thereon controlling the position of the plate, a crank arm on the shaft, a dog engaging and holding the crank arm, and means operated when the cylinder fails to take a sheet of paper, to release the dog from the crank arm and permit the type supporting plate to fall from its printing position.
10. In a printing press, the combination with a vertically movable type supporting plate, and an impression cylinder constructed to move across the same, of a shaft eccentric theron constructed when in one position to hold the plate elevated in printing position, a crank arm on the shaft, and means controlled by the feed of paper to the impression cylinder to change the position of the arm and permit the type supporting plate to fall when the cylinder fails to take a sheet to be printed upon.
15. In a printing press, the combination with a vertically movable type support and an impression cylinder constructed to move around the same, a crank arm controlling the position of the type support, means operated by a sheet of paper as it is drawn to the cylinder for moving the crank arm to a position to hold the type support in normal printing position and means for moving the crank arm in the other direction to lower the type support, when the cylinder fails to take a sheet of paper.
20. In a printing press, the combination with a vertically movable type supporting plate, and an impression cylinder constructed to roll across the same, of a feed table having a forward hinged section in position to be elevated by the cylinder, gripper fingers on the cylinder to grasp a sheet of paper on the feed table, a wheel constructed to be elevated and turned by a sheet of paper when the latter is drawn onto the cylinder, and mechanism holding the type support elevated or elevating the same, when the wheel is operated by a sheet of paper and said mechanism permitting the type support to lower when the wheel is not turned.
25. In a printing press, the combination with a type support and gear wheels at opposite sides thereof locked to turn together, of an impression cylinder carried by the gear wheels, inking rolls carried by the gear wheels, an ink supply roll carried by the type support inside the path of movement of the impression cylinder and with which some of said ink rolls contact, an ink plate on which the rolls spread the ink and from which other of said rolls receive the ink and ink the type as they move across the same.
30. In a printing press, the combination with a type support and a rotary carriage consisting of gear wheels and connecting means, of an impression cylinder carried
- around the type support by the carriage, inking rolls carried around the type support by the carriage, an ink supply roller, an inking plate, means for preventing contact of certain of said inking rolls with the ink supply roller but compelling said last-mentioned rolls to contact with the inking plate and move over the type while the other inking rolls are held away from the type.
35. In a printing press, the combination with a type support and gear wheels at opposite sides thereof, of an impression cylinder carried by the gear wheels and moved thereby across the type on said support, inking rolls carried by the gear wheels, an ink reservoir located on the type support, and means permitting the ink reservoir to move out of operative position should the cylinder fail to take a sheet of paper to be printed upon.
40. In a printing press, the combination with a type support, and gear wheels at opposite sides thereof, of an impression cylinder carried around the type support, means for revolving the cylinder as it is moved by the gear wheels, means on the cylinder for grasping a sheet of paper to be wound thereon, inking rolls carried by the gear wheels, an ink supply roller with which the inking rolls make contact, and mechanism controlled by the feed of paper for holding the type and ink supply roller in operative position.
45. In a printing press, the combination with a type support and gear wheels at opposite sides thereof, of an impression cylinder supported by the gear wheels and carried thereby around the type support, a type chase on the support, springs between one end of the type chase and the support, and a screw at the other end clamping the type chase at any adjustment on the support.
50. In a printing press, the combination with a movable type supporting plate, and an impression cylinder constructed to roll across the same, of a feed table having a forward hinged section in position to be elevated by the cylinder, gripper fingers on the cylinder to grasp a sheet of paper on the feed table, a wheel constructed to be elevated and turned by a sheet of paper when the latter is drawn onto the cylinder, a rock shaft controlling the position of the type supporting plate, a fork on said shaft with fingers at its ends, a sliding sleeve having fingers to engage the fingers of the fork and rock the same in either direction according to the fingers in engagement, and a cam operated by the wheel to move the sleeve and compel the fingers to engage and hold the type supporting plate elevated and permit the other fingers to engage to drop the type supporting plate when the wheel is not turned due to the failure to feed a sheet of paper.
55. In testimony whereof, I have signed this specification in the presence of two subscribing witnesses.

CARL F. BUCK.
